US00D618981S

(12) **United States Design Patent**
Gringer

(10) **Patent No.:** **US D618,981 S**
(45) **Date of Patent:** **** Jul. 6, 2010**

(54) **TOOL HANDLE**

3,250,000 A 5/1966 Schumman

(75) Inventor: **Donald Gringer**, New York, NY (US)

(73) Assignee: **Allway Tools, Inc.**, Bronx, NY (US)

(Continued)

(**) Term: **14 Years**

(21) Appl. No.: **29/345,171**

FOREIGN PATENT DOCUMENTS

(22) Filed: **Oct. 12, 2009**

WO 2000/06347 2/2000

(51) **LOC (9) Cl.** **08-05**

(52) **U.S. Cl.** **D8/107; D32/41; D32/52**

(57) **CLAIM**

The ornamental design for a tool handle, as shown and described.

DESCRIPTION

FIG. 1 is a top, front and left side perspective view of a tool handle showing my new design;

FIG. 2 is a top view thereof;

FIG. 3 is a left side elevational view thereof, with the right side elevational view being a mirror image;

FIG. 4 is a front elevational view thereof, with the rear elevational view being a mirror image; and,

FIG. 5 is a bottom view thereof.

The dotted lines in FIG. 1, which include a representation of scraper head, are included for the purpose of illustrating environmental structure and form no part of the claimed design.

1 Claim, 3 Drawing Sheets
